UNITED STATES PATENT OFFICE

GUNNAR ROSENQVIST, OF PITTSBURGH, PENNSYLVANIA

CASKET

Application filed August 1, 1928. Serial No. 296,839.

This invention relates to apparatus for making hollow articles of galvanoplastic material more particularly for the making of burial receptacles such as caskets or the like.

5 The present application is a continuation, in part, of an application bearing Serial Number 220,945, filed September 21, 1927, which discloses a method and apparatus for making one-piece seamless caskets by electrolytic deposition.

10 The present invention has among its objects the provision of special apparatus for making caskets or other hollow articles by electrolytic deposition.

15 One object of the invention is to provide special forms and arrangements of anodes adapted for cooperation with a mold for the making of caskets of desirable ornamental configuration and form.

20 In carrying out my invention, I utilize a metal mold comprising a plurality of sections which are arranged when joined to constitute an integral mold of the shape and dimensions of the article to be formed. In carrying out the process the mold is constituted 25 a container or vat for an electrolytic solution which submerges the entire receiving surface of the mold on which the deposition is to be made as well as the anodes which are suspended therein in a particular manner as will be hereinafter described.

In the making of hollow articles of irregular shape and form by electrolytic deposition in accordance with methods heretofore practiced, it is difficult to maintain an even current density. I have found that a substantially uniform current density conducive to the formation of deposits of substantially uniform thickness is obtained by forming the 35 anodes or the portion of the anodes adjacent the face or surface of the mold on which the deposit is to be made, complementary to the contour of the latter.

40 I have also found that when the mold is made with sharp intersecting faces or projections it is necessary to isolate the portion of the anodes adjacent thereto to obtain uniform current density which prevents the formation of excess metal at such portions. If 45 such precautions are not taken, excess metal

will form on the projecting portions of the mold which builds up rapidly to contact with the anode resulting in a short circuit across the anode and mold.

55 One of the principal objects of the invention is the provision of inserts such as handle brackets and hinge lugs on the galvanoplastic metal and in accordance with the invention, such inserts are formed integrally with the deposited metal without the use of rivets, solder or welding.

60 The invention further contemplates the provision of apparatus which is especially adapted for the making of hollow articles of relatively large sizes such as burial caskets in an expedient and efficient manner whereby such articles may be produced in relatively 65 large quantities in an economical manner.

70 In the accompanying drawings constituting a part hereof, and in which like reference characters designate like parts, Fig. 1 is a vertical sectional view of a casket mold and associated apparatus embodying the principles of my invention, and Fig. 2 a top plan view thereof.

75 The apparatus of Fig. 1 comprises a sectional mold consisting of a base 1, side portions 2 and end portions 3, Fig. 2, which are joined at their flanged portions 4 by screw bolts 5 or in any other suitable manner to constitute a unitary mold capable of containing 80 an electrolytic solution. The inner dimensions of the mold are that of the outer dimensions of the article to be formed and the inner surfaces of the mold on which the electrolytic solution is to be formed is of the shape and configuration desired on the outer surface of the finished article.

85 The mold is further provided with apertures or recesses 6 for receiving inserts 7 which are made integral with the metal deposit on the surface of the mold to constitute ear lugs for handle brackets or the like which are attached to the casket in a manner to be herein- 90 after stated. The base 1 of the casket is provided with depressions 8 in spaced apart relation at the respective corners of the mold to produce excess metal for hand grips. When the completed casket is removed from the 95 mold, the deposits 8 are pressed upwardly to 100

project to the interior of the casket chamber thereby forming the handle grips. By so displacing the metal formed in the deposit 8 of the mold, it will be projecting inwardly in 5 the same manner as it projects downwardly after the molding operation.

The mold is provided with flanges 9 extending around its upper edges for receiving clamp-bolts 10 which secure a frame 11 there- 10 to. The frame portion 11 is provided with transverse supports 12 which project through a plurality of anodes 13 to hold the latter in proper spaced relation in proximity with the inner surface of the mold. The anodes 13 15 may consist of solid metal formed in the manner illustrated in Fig. 1 but are preferably perforated receptacles adapted to receive scrap metal 14 which is disposed adjacent to a perforated wall 15 of lead or other suitable 20 material. The perforated members are secured to a frame 16 of wood or other suitable material provided with openings 17 for receiving the transverse supports 12 on which they are movably mounted.

25 The anodes for convenience of handling and to permit moving them in and out of the mold, are made up in sections which are arranged and disposed in the mold in the manner shown in Fig. 2 in which a plurality of 30 such baskets or anodes are disposed in parallel relation along the side walls of the mold and one or more anodes are disposed in proximity with the end walls of the mold, all of the anodes being electrically connected by leads 35 18 to a conductor 19 constituting one leg of a source of electric currents.

As shown in Fig. 1 the perforated walls 40 of the anodes adjacent the side and end walls of the mold are shaped to correspond substantially to the contour of the inner surface of the mold and as shown in Fig. 2, the lead wall sections 15 of the anodes are substantially abutting or may be so when the anodes are 45 assembled in their working position. The wood frame portion 16 of the anode baskets are provided with a chamfer 20 at their edge adjacent the corners of the walls 15 to provide access of the scrap metal and the electrolytic solution to the perforations in or near 50 the extreme edge of the perforated wall.

55 As shown in Fig. 1, the outer perforated walls of the anodes are provided with isolating sections 21 of lead or other suitable material which cover up the perforations in the walls 15 adjacent the sharp projecting portions of the mold to obtain proper current density for the purpose of preventing a direct action between the anodes and the projections of the mold.

60 The inner edges of the upper portions of the mold wall sections 2 and 3 are adapted to receive a sealer frame 23 which is temporarily held in intimate contact with the mold 65 sections by clamping it between the frame portion 11 and the flange 9 of the mold sec-

tions. A rubber liner 24 and a strip or liner 25 are secured to the mold or frame 11 as shown, and are adapted to project beyond the upper edge of the mold to provide a baffle which prevents the deposition of metal on 70 the portion of the sealer frame 23 with which the strip or liner is in contact. The mold is electrically connected by leads 26 to a source of electric current which constitutes the other leg of the line 19, one leg of which is 75 connected to the anodes 13 by leads 18.

The mold is not suspended in an electrolytic solution as commonly practiced in the making of articles by galvanoplastic process, but is preferably placed on or approximate 80 to a separate vat or container 28 in which the electrolytic solution is stored and from which it is conducted to the anodes 13 by a feed line 29 that connects to a pump 30 which is provided with outlet pipes 31 that project 85 into the anodes. A return drain pipe 32 is provided which projects through the frame portion 11 on top of the mold which is the level at which the solution is maintained in 90 the mold.

When current is applied to the anodes and mold, pump 30 is actuated to maintain circulation of the electrolytic solution in the mold for the duration of the process of making electrolytic deposition on the inner surface of the mold. The process is continued until a deposit of desired thickness has been made on the surface of the mold and is then interrupted by disconnecting the electric circuit from the current source. The mold is then dismembered by first laterally moving the anodes on their supports or supporting bars 12 to bring them together so that the lower extending portions of the anodes will clear the upper constructed portions of the 105 mold and all of the anodes are lifted out of the mold or the mold may be lowered away from the anodes as desired. The sections 2 and 3 of the mold are dismembered and the finished casket which is a one-piece integral 110 member is removed. The portions of the finished article corresponding to and which were formed on the depressions 8 of the base of the mold are pressed inwardly in a suitable manner to provide depressions in the casket at the respective corners which constitute hand grips for handling the casket 115 in its manufacture.

On account of the fact that the outer surface of the finished casket is the surface adjacent the mold, it will possess a smooth finish when removed from the mold which eliminates buffing and polishing operations which are necessary when the surface adjacent the anodes constitutes the outer surface 120 of articles made of galvanoplastic metal.

125 It is evident from the foregoing description of my invention that the apparatus for making hollow caskets as hereinbefore set forth, is simple and economical and adapted for the 130

manufacture of caskets of pleasing and ornamental shapes and configurations.

Although the invention has been illustrated as embodied in the manufacture of burial receptacles, it will be obvious to those skilled in the art that it is adapted for use generally where it is desired to form hollow articles in the manner stated and any article of galvanoplastic metal with inserts formed integrally therewith without departing from the principles herein set forth.

The term "anode member" as used in the claims, refers to either the perforated basket or baskets for anode material or the solid blocks of anode material.

I claim:

1. The combination with a liquid containing cathode of an expansible anode member supported entirely from outside the cathode constructed to deposit a substantially uniform thickness of metal on the cathode walls.

2. The combination with a liquid containing cathode undercut on the inside, of an expansible anode member, the expansible anode being constructed in a number of substantially rigid sections longitudinally of the cathode and separately removable therefrom.

3. The combination with a liquid containing cathode undercut on the inside and having a constricted portion above the undercut part, of an expansible and substantially inflexible anode, the dimensions of the anode across the lower portion expanded and in place adjacent the undercut part of the cathode being greater than the inner corresponding dimension at the constricted part of the cathode.

4. The combination with a cathode, of an inflexible anode expansible both laterally and longitudinally of the cathode.

5. The combination with a liquid tight cathode adapted to receive a galvanoplastic deposit on the inner surface, and having a supporting flange around the top thereof, a frame member extending above said flange, transverse members supported on said frame member and extending across said cathode, perforated anode containers supported on said transverse members and adjustable along said members transversely of the cathode.

6. The combination with a liquid tight cathode adapted to receive a galvanoplastic deposit on the inner surface, of a material extending around the top of the cathode and adapted to be free of deposit, a pair of spaced containers for pieces of anode metal within the cathode and supported from above the bottom of said material to be out of contact with the side and bottom cathode walls, said containers being perforated on at least the bottom and side portions adjacent the cathode walls.

7. The combination with a liquid tight cathode for galvanoplastic metal, of a plurality of perforate containers therein for pieces of anode metal and means for support-

ing said containers from above the cathode and permitting adjustment of each container longitudinally or transversely of the cathode.

8. The combination with a metal liquid-containing galvanoplastic cathode, of an anode removably suspended therein from above and out of contact with the cathode surfaces, the horizontal cross section area of said anode being larger in the lower portion than in the upper portion of the cathode thereby to facilitate current conductance through the lower portion of said anode to the lower side wall of the cathode and to the bottom thereof.

9. The combination of a liquid-containing cathode forming one electrode and a plurality of electrode sections supported in said cathode some of said sections being adjustable laterally of the cathode and at least one of said sections being adjustable longitudinally of the cathode independently of said laterally adjustable sections.

10. An apparatus for the electro-deposition of burial caskets comprising a liquid containing cathode shaped to substantially the contour of the casket to be deposited and an anode wider between portions of opposite walls than are the adjacent opposite walls of the cathode at a high elevation, said cathode being formed in a plurality of sections connected by liquid tight joints and said anode comprising a substantially insoluble perforated container for pieces of material to be electro deposited upon the side walls and bottom of the cathode.

11. The combination with a liquid tight cathode forming a receptacle for electrolyte and for receiving a deposit of galvanoplastic metal, of a plurality of perforate anode baskets separately supported within said cathode and each containing pieces of metal to be deposited, some of said baskets including therein an inner means for holding the pieces of metal therein of non-uniform depth and higher adjacent a cathode side of the anode baskets than throughout a portion of the bottom of the basket nearer the center of the receptacle.

12. The combination with a liquid tight cathode receptacle for electrolyte and for receiving a deposit of galvanoplastic metal, of a plurality of perforate anode baskets separately supported within said cathode receptacle and adapted for independent adjustment toward and from a cathode wall and adapted to contain pieces of metal to be deposited.

13. The combination with a liquid tight elongated cathode receptacle for electrolyte and for receiving a deposit of galvanoplastic metal, of a plurality of anode baskets separately supported from outside the cathode and arranged side by side in the receptacle throughout most of its length and adapted for adjustment toward and from the receptacle end walls independently of each other, said

baskets being filled with pieces of anode metal to be deposited and at least those baskets intermediate the end baskets having therein means for holding the anode pieces 5 banked higher adjacent a cathode side of the basket than over some of the basket bottom.

14. The combination with a liquid tight elongated cathode receptacle for electrolyte and for receiving a deposit of galvanoplastic 10 metal on the bottom and side and end walls of a plurality of anode baskets separately supported from outside the cathode and arranged side by side in the receptacle throughout most of its length and adapted for adjustment toward and from each other and toward 15 and from the receptacle end walls independently of each other, said baskets being filled with pieces of anode metal to be deposited and there being such a number of baskets 20 that when aligned longitudinally within the receptacle the end baskets will be about the same distance from the receptacle end walls that the longitudinal side walls of the receptacle are spaced from the baskets.

25 In testimony whereof I have hereunto set my hand.

GUNNAR ROSENQVIST.
